CHARLES E. WARD, OF CHARLESTON, WEST VIRGINIA, ASSIGNOR TO THE CHARLES WARD ENGINEERING WORKS, OF CHARLESTON, WEST VIRGINIA, A CORPORATION OF WEST VIRGINIA.

RUDDER CONSTRUCTION FOR TOWBOATS.

Application filed April 8, 1925. Serial No. 21,680.

To all whom it may concern:

Be it known that I, CHARLES E. WARD, a citizen of the United States, residing at Charleston, in the county of Kanawha and State of West Virginia, have invented certain new and useful Improvements in Rudder Constructions for Towboats; and I do hereby declare the following to be a full, clear, and exact description of the invention, such as will enable others skilled in the art to which it appertains to make and use the same.

This invention relates to rudder constructions for tow boats and has for its object to provide a construction more efficient in use than those heretofore proposed.

With these and other objects in view, the invention consists in the novel details of construction and combinations of parts more fully hereinafter disclosed and particularly pointed out in the claims.

Referring to the drawings, forming a part of this specification, in which like numerals designate like parts in all the views;

Figure 1 is a diagrammatic top plan view of the stern of a boat made in accordance with this invention;

Figure 2 is a longitudinal sectional view taken on the line 2—2 of Fig. 1 and looking in the direction of the arrows;

Figure 3 is a transverse sectional view taken on the line 3—3 of Fig. 1 and looking in the direction of the arrows;

Figure 4 is a diagrammatic top plan view similar to Fig. 1 illustrating a modified form of the invention;

Figure 5 is a diagrammatic view showing the arrangement of parts when desired to move a tow boat in one direction; and

Figure 6 is a diagrammatic view similar to Fig. 5 illustrating the arrangement of parts when desired to move the boat in a different direction.

A tow boat is generally indicated at 1 and comprises the main bottom 2, the sides 3, and the stern 4. The main bottom 2 is substantially parallel with the gun-wales 5 and the waterline indicated by the line 6, see Fig. 2. Near the stern, the bottom 2 is inclined upwardly as indicated at 10 and is provided with a plurality of tunnels or chambers 11, as well understood in ships of this character and as clearly shown in the drawings. The

bottom 10 in forming these tunnels 11 also forms a secondary bottom 12, as clearly shown in Figs. 2 and 3, which is substantially parallel to the aforesaid waterline 6 and slightly therebelow.

The cross section of the tunnels 11 at the deepest portions thereof is circular and with in this circular formation are located the screw propellers 15 mounted on the shafts 16 and journaled as diagrammatically illustrated at 17 in the drawings. The propellers and their shafts, together with the tunnels 11 associated therewith, are all so disposed relative to each other that each propeller 15 will be located in a tunnel 11, and above the main bottom 2 of the boat, see Fig. 3. Further, the propellers 15 are disposed in a common transverse plane as represented by the line 20 in Fig. 1.

With special reference to Figs. 1, 2 and 3, it will be observed that there is provided a plurality of rudders 21 whose stems or axes 22 are located in the same transverse plane 20 with the propellers 15, and that the top surfaces of the rudders 21 are substantially flush with the secondary bottom 12. The rudders 21 are further disposed adjacent the propellers 15 so that there is a propeller 15 located between each pair of rudders 21, whereby each rudder 21 is free to swing in either direction about its stem 22 without interfering with the propellers 15.

Cooperating with the middle rudder 21 is a forward rudder 25 whose stem 26, together with the stem 22 of the middle aft rudder 21, is located in the same longitudinal plane of the tow-boat, and further, said stem 26 is so spaced from said stem 22 that the adjacent ends of the said rudders 21 and 25 will just pass each other when operated, see Figs. 1 and 2. Also the stem 26 of the rudder 25 is located substantially in the same transverse plane, parallel to the plane 20, and passing through the points 28 where the portions of the secondary bottom 12 meet the inclined bottom 10. In other words, the stem 26 of the forward rudder 25 is substantially disposed at the forward end of each adjacent tunnel 11 for a purpose as will presently appear.

All of the aft rudders 21 and the forward rudder 25 are worked in unison. That is to say, no one of these rudders can be turned

without turning to the same degree and in the same direction each of the other rudders of the ship, all being linked together in any well known and suitable way, not shown. With special reference to Fig. 1, it will therefore be seen that when the tow boat 1 is moving in a direction straight ahead, the rudders 21 and 25 will be in the positions shown in full lines, whereas when the course of the tow boat is changed, all of the rudders 21 and 25 will be thrown to such positions for example as indicated by the thin dash lines 30.

In the modified form of the invention shown in Fig. 4, the same construction as illustrated in Fig. 1 has been followed, except for the addition of two extra forward rudders 25, each stem 26 thereof being located in the same longitudinal plane with the stems 22 of the rudders 21, and said stems 36 being in the same transverse plane with the stem 26 of the middle forward rudder 25. In other words, there has been added in the modified form two rudders, one on each side of the aforementioned rudder 25, so that there are provided triple longitudinally disposed pairs of rudders. As in the type illustrated in Fig. 1, the rudders of the modified form are likewise linked together in any well known manner (not shown) by means of which all the rudders are operated in unison.

With special reference to Fig. 5 wherein the propellers 15 are being revolved to force the water therefrom in the direction of the small arrows, it will be seen that the boat 1 would be propelled forward or in the direction indicated by the large arrow. While traveling in this direction, if it is desired to change the course so as to swing the prow of the boat to starboard, or to the right, then the rudders 21 and 25 would be positioned as shown in Fig. 5, whereupon the stern 4 would be swung in the direction of the little arrow or to such a position as indicated by the dash line 40.

The reason for this will be readily seen, but may be stated as follows: When the rudders are set as shown in said Figure 5, the water indicated by the line of arrows 41 will strike the obliquely disposed blades of the rudders with the tendency toward deflection therefrom, but as is well known, in this action, the boat would yield and therefore assume such a position as indicated at 40.

With reference to Fig. 6, practically the opposite of what has been said above takes place. That is to say, when the revolution of the propellers 15 is reversed so as to force the water therefrom in the direction of the short arrows 42, and the rudders 21 and 25 are set as shown, then the stern 3 would be given a flanking movement in the direction of the small arrow whereupon said stern 65 would assume a position as indicated by

the dash line 45, thus swinging the boat in the opposite direction from that described in Fig. 5.

It has been found possible in a boat being propelled forward at full speed and provided with the construction above disclosed to reverse the propellers and turn the same full speed aft in order to swing the boat 1 in the direction desired without damage thereto.

The purpose of arranging the rudders 21 and 25 as above described is to form channels for the water passing said rudders. With particular reference to Figs. 3, 4 and 5, it will be seen that when the rudders are set for straight ahead, said rudders will form parallel channels disposed longitudinally of the boat and through which the water may pass. Stated in still other language the forward star-board rudder 35, together with its cooperating aft rudder 21, forms a wall or partition. Likewise, the middle forward rudder 25 forms with its co-operating aft rudder 21, another wall which with the aforementioned wall forms a water channel such as is indicated at 50 in Fig. 3. In a similar manner the opposite outward or port pair of rudders 21 and 35 forms a wall of the channel 51, see Fig. 3, of which the middle pair of rudders 21 and 35 constitutes the other wall.

When the rudders are put hard over or in such a position as illustrated in Fig. 5, there is still provided a channel for the water. In this instance, however, the middle forward rudder 25 cooperates with the outer starboard rudder 21 to form therewith a wall or partition forming one side of a channel 52 whose other side is formed by the middle rear rudder 21. With such a channel formed, the water will pass in the direction of the arrows 53, all as will be clear from Fig. 5. Likewise the middle aft rudder will form with the aft port or other outer rudder 21 a channel 54.

In other words, due to the fact that all of the rudders are linked together and therefore operated in unison all rudders will be at all times parallelly disposed toward each other. Also, the forward rudders will form with the rearward rudders water channels with a propeller therein said channels being disposed below the bottom of the boat.

It is obvious that those skilled in the art may vary the details of construction as well as the arrangements of parts without departing from the spirit of the invention, and therefor it is not desired to be limited to the above disclosure except as may be required by the claims.

What is claimed is:—

1. In a tow boat the combination of a plurality of chambers; a propeller located in each chamber; pair of rudders associated with each chamber; and an additional rud-

der longitudinally disposed to one of the
rudders in said pair of rudders.

2. In a tow boat the combination of a plurality of transversely disposed and longitudinally extending chambers the sides of which terminate in a stern bottom lying in a plane substantially parallel to and slightly below the surface of the water; a propeller located in each chamber; a pair of rudders associated with each chamber; and an additional rudder longitudinally disposed to one of the rudders in said pair of rudders.

3. In a tow boat the combination of a plurality of chambers whose centers lie in the same transverse plane; a propeller located in each chamber and in said plane; a pair of rudders associated with each chamber and mounted in said plane; and an additional rudder longitudinally disposed to one of said first named rudders and mounted in the plane passing substantially through the forward ends of said chambers and parallel to said first mentioned plane.

4. In a tow boat of the chambered type the combination of a plurality of transversely disposed and longitudinally extending chambers the sides of which terminate in a stern bottom lying in a plane substantially parallel to and slightly beneath the surface of the water; a plurality of aft rudders mounted in the transverse plane passing substantially through the centers of said chambers; a propeller located in each chamber and in the said transverse plane of said chambers and aft rudders; and a forward rudder coacting with one of the aft rudders to form a channel for the water set in motion by one of said propellers.

5. In a tow boat of the chambered type the combination of a plurality of transversely disposed and longitudinally extending chambers the sides of which terminate in a stern bottom lying in a plane substantially parallel to and slightly beneath the surface of the water but above the main bottom of the boat; a plurality of aft rudders disposed below said stern bottom but above the main bottom and mounted in the transverse plane passing substantially through the centers of said chambers; a propeller located in each chamber and in the said transverse plane of said chambers and aft rudders; and a forward rudder coacting with one of the aft rudders to form a channel for the water set in motion by one of said propellers.

6. In a tow boat of the chambered type the combination of a plurality of transversely disposed and longitudinally extending chambers the sides of which terminate in a stern bottom lying in a plane substantially parallel to and slightly beneath the surface of the water; a plurality of aft rudders mounted in the transverse plane passing substantially through the centers of said chambers;

bers; a propeller located in each chamber and in the said transverse plane of said chambers and aft rudders; and a forward rudder mounted in the transverse plane passing substantially through the forward ends of the said chambers coacting with one of the aft rudders to form a channel for the water set in motion by one of said propellers.

7. In a tow boat of the chambered type the combination of a plurality of transversely disposed and longitudinally extending chambers the sides of which terminate in a stern bottom lying in a plane substantially parallel to and slightly beneath the surface of the water; a plurality of aft rudders mounted in the transverse plane passing substantially through the centers of said chambers; a propeller located in each chamber and in the said transverse plane of said chambers and aft rudders; and a forward rudder mounted in the transverse plane passing substantially through the forward ends of the said chambers and in the same longitudinal plane with one of said aft rudders, said forward rudder coacting with one of the aft rudders to form a channel for the water set in motion by one of said propellers.

8. In a tow boat of the chambered type, the combination with a plurality of chambers of a plurality of rudders mounted in transverse and longitudinal planes below and adjacent said chambers; and a plurality of propellers, one in each chamber, each propeller associated with a transverse pair of rudders to set in motion the water therebetween.

9. In a tow boat of the chambered type, the combination with a plurality of chambers of a plurality of rudders mounted in a plurality of transverse and longitudinal planes below and adjacent said chambers one of said transverse planes passing substantially through the centers of said chambers and the other transverse plane passing substantially through the forward ends of said chambers; and a plurality of propellers, one in each chamber, each propeller associated with a transverse pair of rudders to set in motion the water therebetween.

10. In a tow boat of the chambered type, the combination with a plurality of chambers of a plurality of rudders mounted in transverse and longitudinal planes below and adjacent said chambers; and a plurality of propellers located within the outer longitudinal planes of said rudders, one propeller in each chamber, each propeller associated with a transverse pair of rudders to set in motion the water therebetween.

11. In a tow boat of the chambered type, the combination with a plurality of chambers of a plurality of rudders mounted in transverse and longitudinal planes below

and adjacent said chambers; and a plurality of propellers located in one of the transverse planes of said rudders, one in each chamber, each propeller associated with a transverse pair of rudders to set in motion the water therebetween.

12. In a tow boat of the chambered type, the combination with a plurality of chambers of a plurality of propellers, one in each chamber, disposed in a transverse plane passing substantially through the centers of each chamber; and a plurality of rudders mounted in transverse and longitudinal planes below and adjacent said chambers, each rudder of one transverse plane coacting with one of the rudders in the other trans-

verse plane to form a channel for the water set in motion by one of said propellers.

13. In a tow boat of the chambered type the combination of a plurality of aft rudders located in a transverse plane; a plurality of forward rudders located in a plane parallel to said transverse plane as well as in the same longitudinal planes of said aft rudders; a plurality of chambers located above and between said aft rudders; and a propeller in each chamber to set in motion the water therein as well as the water in the channel formed by the adjacent aft rudders and each associated forward rudder.

In testimony whereof I affix my signature.

CHARLES E. WARD.
